(57) **CLAIM**

The ornamental design for a torque hub, as shown and described.

DESCRIPTION

FIG. 1 is a top right perspective view of a torque hub showing our new design;

FIG. 2 is an elevation view of the front of the torque hub of FIG. 1;

FIG. 3 is an elevation view of the back of the torque hub of FIG. 1;

FIG. 4 is an elevation view of the right side of the torque hub of FIG. 1;

FIG. 5 is an elevation view of the left side of the torque hub of FIG. 1;

FIG. 6 is a plan view of the top of the torque hub of FIG. 1; and,

FIG. 7 is a plan view of the bottom of the torque hub of FIG. 1.

The broken lines shown in the figures are for the purpose of illustrating portions of the torque hub and form no part of the claimed design.

1 Claim, 7 Drawing Sheets
